AUTOMOBILE FLOOR MAT

Urban S. Hirsch, Beverly Hills, and Dewey Latin, Glendale, Calif., assignors to Royal Accessories, Inc., Los Angeles, Calif., a corporation of California

Application June 18, 1956, Serial No. 41,932

Term of patent 3½ years

(Cl. D9—2)

Fig. 1 is a top plan view of an automobile floor mat embodying the new design;

Fig. 2 is a detail fragmentary plan view of a corner of the mat taken in the area 2 in Fig. 1;

Fig. 3 is a cross section taken on line 3—3 in Fig. 2;

Fig. 4 is a cross section taken on line 4—4 in Fig. 2;

Fig. 5 is a detail fragmentary plan view of another corner of the mat taken in the area 5 in Fig. 1;

Fig. 6 is a cross section taken on line 6—6 in Fig. 5;

Fig. 7 is a fragmentary plan view of the crest portion of the mat;

Fig. 8 is a cross section taken on line 8—8 in Fig. 7;

Fig. 9 is a fragmentary section taken on line 9—9 in Fig. 1; and

Fig. 10 is a fragmentary view of the underside of the mat, this being typical of the entire under surface.

The dominant features of our design reside in the portions shown in full lines.

We claim:

The ornamental design for an automobile floor mat, substantially as shown and described.
